UNITED STATES PATENT OFFICE.

JOHN O. NASLIN, OF SEATTLE, WASHINGTON.

DOOR CLOSER.

Application filed October 23, 1923. Serial No. 670,280.

To all whom it may concern:

Be it known that I, JOHN O. NASLIN, a citizen of the United States, residing at 415 Taylor Avenue, in the city of Seattle, county 5 of King, and State of Washington, have invented a new and useful Door Closer; and I do hereby declare that the following is a full and exact description thereof, reference being had to the accompanying drawings and the characters and references 10 marked thereon.

My invention relates to a door closer, by which a door and the like, is rendered self-closing with less spring-strain and, the well-known annoyance of slamming, almost entirely 15 eliminated; and, besides being simple in construction and durable, it is adapted for right and left-hand swinging doors; and for both sides thereof, but operates more satisfactorily on the side thereof facing the 20 jamb.

I attain these objects by the mechanism described herein, and illustrated in the accompanying drawings, wherein—Figure 1 is 25 a view of a door, showing the position of the device thereon, and of casing 4 below, as seen from the front. Figure 2 is a top view of the device, in solid lines when the door is closed, and in dotted lines when it is 30 swung wide open to the wall. Figure 3 is a top view of the counter-balance, and Figure 4 is a front view thereof. Figure 5 is another top view of the device, showing the 35 straight shape of the counter-balance, by solid lines when the door is closed, and by dotted lines when it is swung open to the wall; and Figures 6 and 7 are front and side views of the curved portion “1^c” of the counter-balance.

40 In these figures the same letters and numerals refer to similar parts.

Letter A indicates a door, B a casing, C a jamb and D a hinge; and are named “parts” in the claims.

45 The objects attained by this device are somewhat similar to those attained by my previous inventions, patented October 14, 1919, and November 2, 1920; but the constructions and combinations of this device 50 has no comparison with the former; in some respects it slightly resembles the latter; it is, however, simpler and less expensive to manufacture, in that it contains fewer parts different from the former. The device consists mainly of an ordinary spiral, or tension 55 spring in combination with a counter-

balance, indicated by “1”; which may be constructed in various forms, such as a straight arm or bar, with pivot means attachable to a door, and means for spring and 60 balance-arm connections, as hereinafter described. But such a straight balance is, however, not so practical as a counter-balance, such as shown in Figures 2, 3 and 5; which is pivoted at 2^a to a bracket 2; which 65 by means of screws inserted through holes 2^b, 2^b, is fastened onto a door, near the hinged edge thereof, so that the said balance, when connected as hereinafter described, can freely swing with the opening and closing 70 movements of the door.

The shape of this balance, beginning at the pivoted end thereof, is curved and bent so as to form a suitable abutment at 1^c, 75 against which spring 3 presses and is projected away from the side and edge of door A; which is thereby rendered self-closing all the way from an opening swing of about a half-circle to its closing point. From this curved portion the balance extends outward 80 from the door, forming the projecting means with a plurality of holes at 1^b, 1^b, for the connection of one end of spring 3, and turns into an elbow at 1^d; whence it runs forward 85 in a straight line to the swinging end thereof, at 1^a; where is provided one or more holes, so that it can be used for different sizes of doors, which do not vary too much in size, by adapting and connecting one end 90 “5^a” of balance-arm 5 in one or another of 95 said holes, as may be suitable for the door for which the balance is used. The other end “5^b” of which is connected to the jamb C at 5^c. Thus forming the means for maintaining the said balance in position against 95 the tension of spring 3, as may be required, when the latter is connected to the balance in one or another of holes 1^b, 1^b, therein, and to the door at 3^c. Whereby the door is rendered self-closing with less spring-strain 100 and a firmer closure, than when the said spring is directly connected to the door and to the jamb. For by this device spring 3 is carried with the door during the latter's opening and closing movements, wherefore, 105 by such a combination, said spring is not stretched so far when the door swings open, as when connected directly to the jamb at 5^c. Wherefore it is evidently clear that, by the use of this balance, said spring may be stretched farther at the closing point of 110 the door, and still become less strained when

the door swings open and can also be shorter, than when directly attached to the jamb, as previously stated. Furthermore, by the use of this device such leverage is produced that, when the said arm and the said spring are about in line with each other, the said spring will hold the door closed without any connection to it at 3^c ; but only by stretching it with the hand in the direction shown by solid lines in Figure 2, will the spring hold the door closed. By the use of a straight balance, with only a bent and curved portion at 1^c , (see Figure 5) the swing and closure of the door is not so easy and perfect, as when a balance is used, as shown in Figures 2 and 3; where it is seen how the end of the balance at 1^a 1^a , is positioned much closer to the door, than as shown in Figure 5. And it is for this reason that, by the use of a balance as shown in the last named figure, the tension of spring 3 is lessened at the closing point of the door; but increased more at its opening swing, than by the use of a balance, as indicated in Figures 2 and 3. Whereby, if of proper size and form, with proper adjustments and spring-connections, as shown and specified, a door can be rendered self-closing in an easy-going manner without any slamming.

From the foregoing it may be understood, that the size of this balance and spring should correspond in size as nearly as possible to the size and dimension of the door, for which they are to be used, but a balance and a spring made for a large door can be used for a smaller one, if not too great a difference exists, by merely shortening and connecting arm 5 in some hole at 1^a 1^a , positioned nearer to the door; and as to a certain degree the effect of the tension of spring 3 on the door, depends upon the pitch or projection of the former from the latter, the tension of said spring may, consequently, be increased or decreased by it being connected in one or another in holes 1^b 1^b , nearer to, or farther from the door for which it is used. The tension of said spring can also be adjusted by moving its fastening at 3^c one way or another, or merely turning rod-hook 3^b at that point, as may be required for obtaining more or less tension for the proper closing of the door.

I have provided a roll or casing, whereby to enclose and shield spring 3, that should be of suitable form and dimension for the free movement therein of said spring; and it has the end near 3^c contracted about rod-hook 3^b , so as to remain stationary at that point. While the other end thereof is left open, for the inward and outward movements of said spring, or hook 3^d , when said spring is expanding and contracting, during the opening and closing movements of the door.

It may be possible that this device can be

constructed in various other forms, than what I have herein described, without change in principle, wherefore, I hereby reserve the right to use all other forms of constructions, which involve the same principles 70 as herein specified.

What I claim is:

1. In a door closer, a counter-balance having a curved end adapted for spring-abutment and pivoted to a hinged part near its hinged edge, an outward projecting swinging end adapted for balance-arm connection, and an intermediate portion adapted for spring connection, spring-means actuating the closing movements of said part, and means for maintaining said balance against the said spring-means. 75

2. In a door closer, a counter-balance having a pivoted end curved for spring-abutment and positioned upon a hinged part near its hinged edge, an intermediate portion extending outward from said abutment and adapted for spring-connection, and a swinging end extending forward from said portion to a point suitable for balance-arm connection, an arm connecting said balance to a stationary part, and a spring connected to said portion and said hinged part, whereby the latter is rendered self-closing. 85

3. In a door closer, a counter-balance having a pivoted end adapted for spring-abutment, a swinging end adapted for balance-arm connection, and an intermediate portion adapted for spring-connection, pivot-means connecting said balance to a hinged part near its hinged edge, spring means for actuating the closing movement of said part, and means for maintaining said balance in position against the tension of said spring means. 90

4. In a door closer, a counter-balance having a forward extending swinging end adapted for variable balance-arm connections, and a pivoted end adapted for spring-abutment and mounted upon a hinged part near its hinged edge, and an outward extending intermediate portion adapted for variable spring-connection, adjustable tension means connected to said portion and said part, and means connected to said end and a stationary part, whereby the said hinged part is rendered self-closing. 100

5. In a door closer, a counter-balance having one end adapted for spring-abutment and pivoted to a hinged part near its hinged edge, the forward extending swinging end of which is adapted for balance-arm connection, and the intermediate portion of which is adapted for spring-connection, spring-means actuating the closing movements of said part, a casing carried by said means and a balance-arm for maintaining the said balance against the tension of said spring-means, as for the purpose shown and specified. 110

95

105

110

115

120

125

130

6. In a door closer, a pivoting bracket positioned upon a hinged part near its hinged edge, and a counter-balance having a curved end adapted for spring-abutment and pivot-
5 ed to said bracket so as to reciprocately swing with said part; the intermediate portion of said balance being extended outward from said abutment to a distance adapted for spring-projection, with a plurality of
10 holes for spring-connection, and the swing- ing end thereof being extended forward to

a distance suitable for balance-arm connec-
tion, for which it is adapted, a spring con-
nected to said portion and said part so as to
actuate the latter's closing movement, a bal-
ance-arm connected to said end and to a sta-
tionary part so as to maintain said balance
against the tension of said spring, and a cas-
ing inclosing said spring, with room and
openings for its movements.

JOHN O. NASLIN.
